UNITED STATES PATENT OFFICE.

AMBROSE EVERTS GREENE, OF MARSHFIELD, OREGON.

VALVE-OPERATING MECHANISM.

No. 902,725.

Specification of Letters Patent.

Patented Nov. 3, 1908.

Application filed June 15, 1907. Serial No. 379,215.

To all whom it may concern:

Be it known that I, AMBROSE EVERTS GREENE, of Marshfield, in the county of Coos and State of Oregon, have invented certain new and useful Improvements in Valve-Operating Mechanism, of which the following is a specification.

This invention relates to valve operating mechanism.

More particularly, it relates to means for operating the valves and ignition of a four-cycle internal combustion engine, and for reversing such engine.

The objects of the invention are to eliminate gear wheels from the valve operating mechanism and substitute therefor a simple reciprocating motion; to effect the ignition under conditions calculated to secure the greatest efficiency, by the same mechanism; and to provide for the ready reversal of the engine.

These objects are accomplished by the mechanism illustrated in the accompanying drawing, which represents one embodiment of the invention.

In the drawings—Figure 1 represents an elevation of the operating mechanism, viewed as if sectioned on line 1—1 of Fig. 3. Fig. 2 is a plan of the same, sectioned on the line 2—2 of Fig. 1. Fig. 3 is a somewhat diagrammatical view showing, in elevation, the relation of these parts to the engine. Figs. 4 and 5 are sectional elevations of a detail seen respectively from the side, as in Fig. 1, and from the front, as in Fig. 3. Figs. 6 and 7 are sectional views showing another detail in side and front views respectively.

In the drawings the invention is represented as it may be applied to an upright engine, the mechanism and general arrangement of which may be of any suitable form.

As here shown, the reference numeral 10 indicates the frame of the engine, within which the cylinder and principal moving parts are contained.

11 is the main driving shaft of the engine, and 12 the driving wheel.

13 is the exhaust pipe, and 14 the lever of a valve 15 therein which is to be controlled through the agency of the mechanism about to be described.

On shaft 11 is a collar 16, holding fast a cam 17 thereon which operates a roller 18. Another collar 19 has a projecting lug or arm 20 which rotates with the cam. Roller 18 is mounted on a lever 21, having a block 22

with a cup-shaped or conical depression 23 in its top, in which is seated the hub 24 of a wheel having four spokes 25. This wheel rotates in the said bearing 23, and may be lubricated as desired. It has an axial pin 26 extending upward, equipped with a cross pin 27. Above, it enters a tube 28, having a cleft 29 in which the cross pin 27 may rise when suitably positioned. Higher up in the tube 28 is a spring 30, and the upper end of the tube is closed so that when the pin 26 rises it compresses spring 30 and is subject to the downward pressure of that spring. A rod 31 forms a continuation of the tube upward, being suitably guided in a bearing at 32, and at its upper end 33 engages valve lever 14. The cross arm 27 has contact points 35, and a suitably insulated spring 36 is stationarily mounted nearby in position for platinum point 37 thereon to make electrical contact with one of the points 35 whenever the pin 26 rises in cleft 29; and the contact is broken when the pin falls. The spring 36 forms part of an electrical circuit, being connected through a conductor 38, which circuit is completed through contacts 37, 35, cross arm 27, pin 26, and through tube 28 or spring 30, or both, to rod 31, and thence through another conductor to the induction coil for causing the spark in the engine, and back to the battery.

In operation, the shaft 11 makes one complete revolution for each two cycles in the engine cylinder, thus engaging one of the spokes 25 and rotating pin 26 one-quarter revolution. As shown in Fig. 1, the cam 17 is in position to raise roller 18, thus raising pin 26; and that pin is in position to enter cleft 29 when so raised, thus making electrical contact between 35 and 37. This corresponds to the beginning of the fourth cycle, the completion of which occurs when the portion 40 of the cam 17 reaches roller 18, allowing that roller to drop, and with it the pin 26, breaking the circuit between 37 and 35. This causes the ignition spark in the combustion chamber of the engine. The next half revolution of the cam carries it again to the position shown in Fig. 1, and while doing so the arm 20 engages the next spoke 25 and turns it and pin 26 one-quarter revolution. This reaches the end of the first cycle, and at the beginning of the second, cam roll raises cross arm 27, which, not being under cleft 29, engages the flat end 41 of the tube 28, lifting the entire tube and rod 31 and the

operating lever 14 to open exhaust valve 15. This remains open during the next half revolution of the cam 17, which is the second cycle; and closes when cam face 40 reaches the roller. During the third cycle pin 26 remains down and arm 20 turns the pin another quarter revolution, so that when roller 18 rises at the beginning of the fourth cycle the cross arm 27 enters the cleft 29 and does not raise tube 28, and therefore does not operate the exhaust valve, but does make the electrical connection as above described.

The rod 31 may preferably be squared in order to prevent its rotation. The edges of the cleft 29 may be beveled or rounded, as indicated, to receive rod 27 unfailingly, even though it be not accurately positioned. When the engine is not designed to be reversible the cam 17 is firmly keyed to shaft 11, but the mechanism may be adapted for operation of the engine in reverse direction by mounting the cam 17 loosely on shaft 11 and providing a key 42 set in the shaft, and a groove 43 in the cam next the shaft, in which the key may slide from the position shown in Fig. 6 until the cam has turned 180 degrees about the shaft. Thus, the groove is made 180 degrees long plus the thickness of the key. A set-screw or other suitable means is provided to lock the cam in either position. Upon the reversing of the cam the position of the arm 20 should be reversed likewise 180 degrees. It is, therefore, convenient in an engine which is designed to be reversible, to form the collars 16 and 19 in one piece, thus making the arm 20 fast with the cam 17 and in fixed relation thereto. This arrangement is indicated in Fig. 7. It will be noted that the rising of cross-arm 27 in groove 29 serves to draw the pin into perfect register with said groove, in case the action of lug 20 may have thrown spoke 25 a little too far or not far enough, thus serving as an automatic adjuster.

By the above described construction or such obvious modifications of it as may be made to suit the particular conditions to which the invention is to be applied, very simple mechanism is provided for actuating the exhaust valve and the ignition alternately. It will be observed that one pin 26 performs both functions and that this is accomplished by imparting to it a step by step rotation, by means of the spokes 25 and lug 20, which alternates with the up-and-down reciprocating movement, which is the actuating stroke, turning the pin successively from a position in which it actuates the valve to a position in which it actuates the ignition, and then to a position in which it actuates the valve again, and so on. The cam gives a sharp and desirably quick opening of the exhaust valve, and the fall of the cam gives likewise a quick drop of the pin 26 which enables the break between points 35

and 37 to be timed with precision. The spoke wheel and its actuating lug 20 effect the necessary changes by mechanism of notably inexpensive construction as compared with gears, and are more compact and less likely to get out of order, are less expensive to repair, and can in fact be repaired if damage occurs at a point remote from a machine shop or a place where proper gears can be obtained.

The parts above described are few in number and can be made in almost any machine or repair shop.

By the precision of action in timing the spark the efficiency of an ordinary engine may be materially increased, because it can be fixed with certainty, to save loss of explosive power resulting from too late ignition, or loss of energy or back firing resulting from too early ignition; and the accuracy with which it can be timed increases the capacity of an engine, because it enables the valve and ignition mechanism to start promptly into operation at the proper time of stroke.

Another feature of the invention which may be added to the above described parts, if desired, to insure certainty of precise action, is the spring 46, which may be supported in any convenient manner, and in the drawings is represented as supported upon the engine body. This spring is forked and embraces the pin 26 on opposite sides. A portion of the pin is squared, as represented at 47. When the pin rotates it causes the two forks of the spring to spread until the diagonal of the squared portion has passed one of them, pressing inward, bringing rotation of the pin to rest at precisely a quarter turn. This spring may be formed in any suitable manner. As represented in Figs. 2 and 3, the forks are portions of a flat spring which have been partly twisted so that they bear flat against the squared pin.

I claim:

1. Valve operating mechanism, including, in combination, a driving shaft having a cam and a lug rotating therewith; a pin reciprocated by the cam and having a series of spokes engaged by the lug; a valve operating rod and an ignition operating device separately actuated by the pin; the rise of the cam occurring alternately with the engagement of said lug with one of said spokes.

2. Valve operating mechanism, including, in combination, a driving shaft having a cam and a lug rotating therewith; a block reciprocated by the cam and having a valve and ignition operating pin projecting therefrom, moving therewith and adapted to be engaged and rotated by the lug, the cam and the lug acting alternately thereon; and means whereby the pin actuates the valve and the ignition at different stages of its rotation.

3. Valve operating mechanism, including, in combination, a driving shaft and an actu-

ating pin alternately reciprocated and rotated fractionally thereby; a valve operating rod having a grooved portion, and an ignition operating device, the latter being in position for engagement with the pin when the pin registers with the opening of the groove, and the former being actuated when it does not so register.

4. Valve operating mechanism, including, in combination, a valve operating rod and a pin arranged to actuate it, one of these parts having a groove and the other a tongue; an ignition operating device registering with the groove; and means to reciprocate and rotate the pin alternately, whereby upon successive reciprocations it alternately registers with the groove, engaging the ignition device, and registers with the rod, actuating the rod.

5. Valve operating mechanism, including, in combination, a valve operating rod having a grooved end; an ignition device having a terminal adjacent to the groove; an actuating pin adapted to rise in the groove and make electrical contact, said pin being rota-

table and adapted to lift the rod and miss the contact when not registering with the groove; a series of spokes projecting from the pin; and a driving shaft having a lug thereon adapted to engage the spokes successively, and a cam adapted for raising and lowering the pin alternately with the action of said lug.

6. Valve operating mechanism, including, in combination, a valve operating rod and means to rotate the rod in successive quarter turns, said rod being squared and there being a flat spring having two prongs embracing the squared rod, said prongs being each twisted a quarter turn from the plane of the shank of the spring, and bearing flatwise upon opposite sides of said squared rod.

In testimony whereof I hereto affix my signature, in presence of two witnesses.

AMBROSE EVERTS GREENE.
